(57) **CLAIM**

The ornamental design for a blanket with straps and closures configurable into different shapes for different uses, as shown and described.

DESCRIPTION

FIG. 1 is a perspective view of the blanket with straps and closures configurable into different shapes for different uses showing my new design in use as a blanket;

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a perspective view of thereof show configured to form a seat cushion.

FIG. 9 is a top view thereof.

FIG. 10 is a front view thereof.

FIG. 11 is a rear view thereof.

FIG. 12 is a bottom side view thereof.

FIG. 13 is a right view thereof.

FIG. 14 is a left view thereof.

FIG. 15 is a perspective view thereof configured to form a double-thick blanket or skirt.

FIG. 16 is a front view thereof.

FIG. 17 is a rear view thereof.

FIG. 18 is a top view thereof.

FIG. 19 is a bottom view thereof.

FIG. 20 is a right view thereof.

FIG. 21 is a left view thereof.

FIG. 22 is a perspective view thereof configured to hold an object securely, such as a folding chair.

FIG. 23 is a front side view thereof.

FIG. 24 is a rear view thereof.

FIG. 25 is a top view thereof.

FIG. 26 is a bottom view thereof.

FIG. 27 is a left side end view thereof; and,

FIG. 28 is a right side view thereof.
